UNITED STATES PATENT OFFICE.

WILLIAM E. SHORE, OF TORONTO, ONTARIO, CANADA, ASSIGNOR OF FORTY ONE-HUNDREDTHS TO JOHN FRANEY AND TWENTY ONE-HUNDREDTHS TO JANE C. FRANEY, OF TORONTO, CANADA.

STOVE.

1,078,315.

Specification of Letters Patent. Patented Nov. 11, 1913.

Application filed December 28, 1912. Serial No. 739,045.

To all whom it may concern:

Be it known that I, WILLIAM EDWARD SHORE, a subject of the King of Great Britain, and resident of the city of Toronto, county of York, Province of Ontario, in the Dominion of Canada, have invented certain new and useful Improvements in Stoves, described in the following specification and illustrated in the accompanying drawings.

10 The principal feature of the invention consists in the novel construction and arrangement of an attachment for stoves whereby a supply of air is superheated and then directed to and distributed in the combustion chamber.

15 The main objects of the invention are, to effect a reduction in the consumption of fuel, and to devise an improvement in stove or furnace construction which will insure the 20 consumption of the maximum amount of combustible matter thereby preventing the escape of unburnt gases from the fire, and obtaining the maximum heat units from the fuel consumed.

25 A further object of the present invention is to reduce the labor of attention to the stove or furnace to the minimum.

30 In the drawings, Figure 1 is a longitudinal sectional view of a stove showing the application of my invention. Fig. 2 is an enlarged perspective detail of the air heating and distributing device for the top part of the stove. Fig. 3 is an underside plan view of the air heating and distributing device 35 shown in Fig. 2.

Like numerals of reference indicate corresponding parts in each figure.

Referring to the drawings, 1 is the stove body having the fire box 2 in the front there- 40 of and the oven 3 separated from the outer shell by the heat chamber 4 extending over the top and around the back and beneath the same.

45 5 is an air chamber arranged beneath the bottom portion of the chamber 4 and extending forwardly from the back of the stove.

6 is a baffle plate extending upwardly from the stove bottom 7 arranged at the 50 back of the ash pit 8 and spaced a short distance forward of the front end 9 of the oven.

10 are a plurality of downwardly sloped louver plates arranged above the open end of the chamber 5 and extending across the

width of the stove below the fire box and 55 forming a guard to prevent the ashes and cinders from falling into the space 11 between the baffle and the front of the oven and also to direct the flow of air from the chamber 5 across the bottom of the grate. 60

12 is a suitable damper arranged in the back of the stove and controlling the ingress of air to the chamber 5. When lighting the fire the damper 12 is opened so as to allow a free ingress of air through the chamber 5. The air flowing inwardly from the back rises at the end of the oven and flows out between the louvers 10 and passes upwardly through the fire. The air supply being thus directed across the bottom of the 70 grate effects a uniform distribution through the fire; consequently the combustion will be uniform and the fire at the back of the fire box adjacent to the oven will always be active. The damper 12 is regulated in a similar manner to the ordinary front damper to control the fire. The air passing through the chamber 5 becomes heated very quickly after the fire has started, consequently a quantity of air rich in oxygen is supplied to 80 the fire at a warm temperature thus creating a better condition for combustion than when cold air is fed direct as in the ordinary construction of stove.

85 13 is a casing, here shown open on the underside and adapted to rest upon the top of the oven 3, the back and front flanges 14 and 15 being preferably of arc shape, though any other desired shape may be used.

16 is a flange formed integral with the top 90 17 of the casing 13 arranged substantially parallel to the back flange 14 and having an opening 18 through the center thereof.

19 is a flange depending from the top 17 and arranged substantially parallel to the 95 flange 16.

20 is a flange also of arc shape arranged parallel to the flange 19 and having an opening 21 through the center thereof.

22 are flanges extending between the outer 100 ends of the flange 20 and the back flange 14 and abutting the ends of the flange 16.

23 are passages around the ends of the flange 19 communicating with the spaces between the flanges 16 and 19 and 20.

24 are holes arranged in the top plate 25 of the oven communicating with the space between the back flange 14 and the flange

16 at the ends of said spaces. The front flange 15 of the casing is formed with a plurality of small holes 26 therethrough.

27 are bosses formed on the top of the 5 casing 13 at the ends having the openings 28 therethrough leading to the interior of said casing.

29 is a tubular loop having the down-turned ends 30 extending into the openings 10 28, said loop being adapted to extend around the ends and across the front of the firebox at the top and having the inner side formed with a plurality of holes 31.

The casing 13 is arranged immediately 15 back of the fire brick lining 32 of the fire box and the edges are preferably cemented to the top of the oven in any suitable manner so that the space contained will be air tight around the edges.

20 33 is an indent formed in the front wall 15 of the casing arranged centrally of its width and adapted to receive the center post 34 of the stove (shown in dotted lines in Fig. 2). The casing thus straddles the 25 post and delivers the heated air directly over the fire.

In the use of this invention, the heated air in the oven rising to the top flows through the holes 26 into the casing 13 and seeking 30 egress flows first through the opening 18 in the flange 16, then around the ends of the flange 19 and through the opening 21 in the flange 20. As the casing 13 is arranged on the top of the oven the gases of combustion 35 rising from the fire pass over the top of said plate; consequently it becomes very hot and the hot air rising from the oven is further heated and flows through expansion outward through the holes in the front side 40 of the casing and mingling with the gases of combustion causes the un-consumed particles thereof to ignite and to give off the heat contained therein. A portion of the air in the front portion of the chamber 45 contained within the casing 13 flows through the openings 28 at the ends and into the tubular loop 29 being distributed around the top of the fire box and directed over the surface of the fire. A supply of heated 50 fresh air is thus distributed over the top of the fire in such a manner as to insure the thorough combustion of all combustible particles of a solid and gaseous nature so that the maximum heat efficiency is obtained and by the arrangement of the under 55 draft there is a uniform distribution of air beneath the grates, consequently the air will pass upwardly uniformly through the fire

effecting a uniform combustion throughout the mass.

I am aware that many devices have been attached to stoves and furnaces in various ways to distribute fresh air in the combustion chamber above the fire, the air being heated more or less before being introduced but so far as I am aware it is entirely novel to introduce heated air into the distributing device where it is subjected to the intense heat of the gases of combustion and super-heated before being distributed. This feature when applied to cook stoves has also another valuable function, in that the odors and vapors created in the oven are completely consumed, thus very materially reducing the escape of odors into the kitchen. The danger of escaping coal gas is also obviated.

What I claim as my invention is:—

1. In an attachment for stoves, the combination with the oven, of a flat hollow casing adapted to be secured to the top plate of the oven and having an opening at the rear communicating with an opening in said oven plate, and a plurality of narrow passages formed between walls extending from the top to bottom, said narrow passages forming superheating chambers for the air rising from the interior of the oven, said casing also having a centrally arranged indent in its front side adapted to straddle the center post of the stove and the inner walls within the casing directing the expanded air in equal volume to each side of said indent delivering the superheated air over the top of the fire pot in a horizontal direction to insure the mixing of the superheated air with the gases of combustion.

2. In a stove, the combination with the fire box and oven, of a casing secured to the top of said oven and having an inlet in the bottom communicating with an opening in the top of the oven and also having openings above the level of the inlet adapted to direct the superheated air into said fire box over the fire, and a tubular member leading from the top of said casing and extending around the top of the fire box and having holes therein adapted to direct the superheated air into the fire box over the fire.

Signed at the city of Toronto, county of York, Ontario, Canada, this 24th day of December 1912.

WILLIAM E. SHORE.
